COAL SAVING SPARK-CATCHER

Eduard Gottschalk, Magdeburg, Germany, assignor to Paul Weile, Magdeburg, Germany

Application June 11, 1931, Serial No. 543,665, and in Germany August 25, 1930

10 Claims. (Cl. 183—78)

Appliances for catching or extinguishing sparks operating with propellers which are caused to rotate in the same or opposite direction to one another are known. A novel feature of this invention is the arrangement of intermediate blades on the propellers which are displaced angularly with respect to the main-blades. They are shorter than the main-blades which extend to within a short distance from the inner surface of the chimney. The hot coal particles passing through the center of the funnel strike the short vanes which cover a wide area of the gas-flow without interfering with the free passage of the burnt gases, as is the case when wire screens, perforated vanes etc. are used which are very liable to become clogged within a short time of action, thereby diminishing the area of flow. The intermediate vanes are also responsible for changing the number of revolutions of the propellers according to their angle and lead. They accelerate the rotation if the angle of the intermediate vanes conforms to that of the main-blades, and if inversely inclined they retard the rotating speed. Hence the velocity of the propellers can be regulated without affecting the ratio of the openings, that is, the quotient of the area covered by the propellers at rest to the area section of the funnel.

For larger diameters of funnel it may be advisable also to provide the upper propeller with intermediate blades.

When the gases are discharged in sudden peridental blows, the blades have to be made flexible so as to guard the supports against rupture. This is accomplished by a steel-spring-attachment located between the hub of the propeller and the bolt-head of the propeller shaft.

Where the quantities of gases passing through the chimney are changing greatly the distance between the propellers must be either increased or decreased as the volume of the flue gas leaving the funnel increases or decreases. This is accomplished by a corresponding adjustment of the springs arranged on the upper propeller. If the spring is relieved by turning the adjusting nut back, the blade deflects automatically and while in operation, thus increasing the space between the two propellers. It will be noticed that this adjustment occurs without changing the location of the support and lubricating system.

A new feature lies also in the fact that the propellers can be brought to perfect alignment with the axis of the funnel. With this arrangement linings in the funnel which entail a decrease of the cross sectional area can be avoided.

The adjusting screws extending through the sides of the smoke stack, by being made with a central bore, also provide for the intake of lubricant and the oil seal at the bearing. A collar-nut secures the screw to the funnel, at the same time protecting the threads against being burnt, furthermore providing a smoke seal.

Another new feature is that the intermediate vanes are so arranged that they can easily be removed from the main-blades. This arrangement not only facilitates the manufacture of those parts but also makes it possible to eliminate the intermediate vanes when it is necessary, or to interchange the upper and the lower vanes so as to obtain a reverse impulse. These possibilities of combination provide for meeting the operating requirements to best advantage.

Referring now to the attached drawing, the particulars of the invention are, as follows:

Fig. I shows an example of installation of the contrivance in elevation with parts in section.

Fig. II gives a partial plan view of the same.

Fig. III is an elevation, partly in section, of a modified form of one of the propeller units.

Within a smoke stack 9 are rotatably mounted two propellers 1 and 2. These propellers are carried by vertical shafts 14 rotatably mounted in ball bearings 15. The propellers 1 and 2 may be keyed to the shafts 14, but have a limited axial movement on their shafts under the restraint of springs 4, the upper ends of which abut against heads 6 of the shafts 14. Fixed to the hub of each of the propellers 1 and 2 is a smaller propeller 3, which has a definite angular position with respect to the larger propeller, the blades being located between the blades of the larger propeller as shown in Fig. II. The smaller propellers increase the obstruction to sparks at the center of the smoke stack where the action of the larger propellers is least because of the lower velocity of the blades near the axis of rotation. The smaller propellers also influence the speed of the larger propellers in accordance with the length and angle of inclination of their blades.

In the modification shown in Fig. III the smaller propeller 12 is located above the large propeller 11 and is axially slidable on the shaft 14, while the larger propeller 11 is fixed to the shaft and does not participate in the axial shifting movement. In this modification the spring 4 is restrained by an adjusting nut 7 by which the tension of the spring can be varied to modify the sliding of the small propeller on the shaft.

In each form of the invention shown, the ball

bearing 15 is mounted at the center of a three-armed spider 16, the arms of which are hollow. At the outer ends the arms 16 are provided with screw threaded sockets 17 into which are threaded adjusting bolts 8 extending through holes in the wall of the smoke stack. Threaded on the adjusting bolts 8 are collar nuts 10, which fit over the holes in the smoke stack and tighten down on packing washers 13. The adjusting bolts 8 are screwed tightly into the sockets 17 and the three collar nuts 10 and washers 13 are tightened against the wall of the smoke stack in proper mutual relation to center the propeller in the smoke stack. The bolts 8 have a central bore communicating with a tube 18 leading through the hollow arm of the spider to the bearing 15. The outer ends of bolts 8 receive the ends of lubricating pipes 19 through which a lubricant can be forced for lubricating the bearings 15.

20 What I claim is:

1. The combination with a locomotive smoke-stack, of spark arresting means comprising two propellers mounted in said stack so as to be independently rotatable about the axis of the stack and having blades inclined to said axis so as to have a torque imparted to them by the fluid current in the stack; at least one of said propellers having connected therewith, in a definite angular relation, a propeller of smaller diameter, whose blades are intermediate the blades of the larger propeller connected therewith.

2. The combination with a locomotive smoke-stack, of spark arresting means comprising two units, each composed of a propeller having a diameter nearly as great as the inner smoke-stack diameter and a supporting spider on which said propeller is rotatably mounted; the space between said units being clear to form a mobile air cushion, the blades of said propellers being 40 reversely inclined with respect to the axis of said stack to cause them to rotate in opposite directions; at least one of said propellers having connected therewith, in a fixed angular relation, a propeller of smaller diameter, the blades of 45 which lie between the blades of the larger propeller connected therewith.

3. A device as described in claim 1, in which the blades of said propeller of smaller diameter are inclined to the axis of said smoke stack at a predetermined angle to modify the speed which would be imparted to the larger propeller connected therewith by the fluid current in the stack.

4. The combination with a locomotive smoke-stack, of spark arresting means comprising two propellers mounted in said stack so as to be rotatable about the axis of the stack, the blades of said propellers being inversely inclined with respect to the axis of the stack to cause them to

be rotated in opposite directions by the fluid current in the stack; each propeller having connected therewith in a fixed angular relation a propeller of smaller diameter, the blades of said smaller propellers lying between the blades of the larger propellers; said smaller propellers having blades of such relative length and inclination as to cause said larger propellers to rotate at a predetermined relative speed.

5. A device as described in claim 1, in which said propeller of smaller diameter is detachably mounted on the larger fan with which it is associated.

6. The combination with a locomotive smoke-stack, of spark arresting means comprising a support in said stack and a propeller yieldably and rotatably mounted on said support and adapted to be rotated by the fluid current in said stack and to be moved axially in said stack in response to changes in pressure.

7. A device as described in claim 6, in combination with regulating means for adjusting the tension of the yieldable mounting of said propeller.

8. The combination with a locomotive smoke-stack of spark arresting means comprising a propeller in said stack mounted for rotation about the axis of said stack and having a diameter nearly as great as the inner diameter of said stack, and a propeller of smaller diameter mounted above said large propeller in fixed angular relation thereto and with its blades between the blades of said large propeller, said small propeller being mounted to shift axially with respect to said large propeller, and yieldable means opposing upward movement of said small propeller.

9. The combination with a locomotive smoke-stack of a three armed spider mounted transversely in said stack by means of adjusting screws at the ends of the arms of said spider passing through holes in the wall of the stack, nuts mounted on said screws and adapted to cover said holes in the wall of the stack and to center said spider in the stack, and a propeller rotatably mounted upon said spider.

10. The combination with a locomotive smoke-stack of a three armed spider mounted transversely in said stack by means of adjusting screws, whereby the spider can be centered in said stack; a bearing at the center of said spider; a shaft rotatably mounted in said bearing; a propeller on said shaft, one of the arms of said spider and the adjusting screw supporting the same having a lubricating duct therethrough leading to said bearing, and means for feeding a lubricant to said duct.
